William Bennett

UNITED STATES PATENT OFFICE.

W. BENNETT, OF NEW YORK, N. Y.

SOCKET FOR TOOL-HANDLES.

Specification of Letters Patent No. 20,693, dated June 29, 1858.

To all whom it may concern:

Be it known that I, WILLIAM BENNETT, of the city and county of New York, in the State of New York, have invented a new and useful Improvement in Sockets for Securing Handles of Wood, &c., to Various Implements of Iron in Common Use; and I do hereby declare the following to be a full, clear, and exact description of my said invention, reference being had to the drawings accompanying and making part of this specification.

The nature of this invention consists in rendering the socket self fastening, so that when the handle is driven home, it becomes permanently fixed and immovable, and not liable to come out as in the ordinary method of fastening. To accomplish this desirable object, I construct the socket in any desired form, whether round or square, so as to receive the handle of any required shape. This socket is made widest at the bottom, and the bottom is closed, or in other words, the socket is only open at one end, and the open end is in all cases the smallest, giving to the socket the form and principle of the dovetail. With this socket I combine the use of the wedge, constructed in any known form, and either united permanently with the bottom of the socket and projecting upward to any required height, by being cast in connection with the socket, or otherwise connected with it in a permanent manner so that when the end of the handle is inserted into the open end of the socket, and driven home, the wedge performs its office by entering the end of the handle within the socket, dividing the same in two or more parts, according to the form of the wedge, and spreading the divided portions apart in such a manner as to completely fill up the lower and widest part of the socket, thus rendering it impossible for the handle to be withdrawn from its position. Or the wedge may be made separate from the socket, and the point entered into the end of the handle before inserting it in the socket so that when the handle is entered and driven home the wedge shall first strike the bottom of the socket and meeting with the resistance thus provided, shall divide the wood as before, crowding it into the lower space at the bottom of the socket and holding the handle permanently as before. This form of construction may include a wedge of

any required shape and of any desired material whether of metal or wood.

This socket is applicable to a great variety of implements in common use, such as hoes, garden rakes, hay and manure forks, coal and other shovels, scoops, &c., &c.

The manner of attaching this socket to the various implements above specified will be by casting them together in some instances, and riveting or welding them in other cases. The socket when designed to be attached by welding, or by rivets, would generally be composed of annealed or malleable iron with a shank or any other requisite appendage for connecting them with the implement.

The advantages resulting from the use of this improved socket will readily be perceived by the intelligent mechanic. In the first instance there is no possibility of the wedge working loose from the fact that it is securely and permanently connected with the socket itself. Neither can this be the case when the loose wedge is employed as the bottom is permanently closed and consequently the wedge can never be withdrawn in that direction.

Figure 1 is a longitudinal section of a socket with the wedge connected permanently with the bottom, in which *a*, *a* represent the opposite sides of the socket and *b* the wedge. Fig. 2 is also a longitudinal section of the same with the handle inserted showing the exact position of the wood with regard to the wedge and the bottom and sides of the socket. Fig. 3 is a sectional view of a socket into the open end of which the handle is entered with the loose wedge inserted into the end ready to be driven to its position within the socket.

I am fully aware that it has long been customary to first insert a wedge into the end of a dowel or pin before driving the same into a straight hole or a space with parallel sides, for the purpose of more effectually securing said dowel or pin in its position.

I am also well aware that the wedge is a well known device for securing the handles of various implements to such implements. It is seen in hoes, axes, hammers, &c., &c., and is invariably inserted in the end of the handle upon the opposite side to the entrance after the handle is driven through the eye or space prepared for it.

I am not aware that the tapering socket involving the principle of the dovetail formed with a closed bottom as herein described with the wedge attached permanently by casting or otherwise has ever been known or used in any form. Neither am I aware that the wedge has first been inserted in the end of the handle of any implement and both driven into a socket with a closed end, having the dovetailed form as herein described.

I do not claim broadly the socket having the form described above when in use independently of the wedge—neither do I claim

the wedge when inserted into the end of a handle and both wedge and handle driven into a socket or space having sides parallel with each other, whether such space or socket be closed or open at the bottom, but I do claim—

A tapering socket made widest at the bottom or closed end in combination with the wedge *b* constructed as herein described and for the purpose specified

WILLIAM BENNETT.
